(57) **CLAIM**

The ornamental design for a brake pedal interconnection unit, as shown and described.

DESCRIPTION

FIG. 1 is a front perspective view of a brake pedal interconnection unit, the broken lines showing environment for illustrative purposes only and forming no part of the claimed design;

FIG. 2 is a front elevation view of the invention illustrated in FIG. 1;

FIG. 3 is a rear elevation view of the invention illustrated in FIG. 1;

FIG. 4 is a right side elevation view of the invention illustrated in FIG. 1;

FIG. 5 is a left side elevation view of the invention illustrated in FIG. 1;

FIG. 6 is a top plan view of the invention illustrated in FIG. 1;

FIG. 7 is a bottom plan view of the invention illustrated in FIG. 1;

FIG. 8 is a rear perspective view of the invention illustrated in FIG. 1;

FIG. 9 is a front perspective view of a second embodiment of the invention illustrated in FIG. 1, the only difference being that a selectively movable portion of the brake pedal interconnection unit is shown in a second position;

FIG. 10 is a perspective view of the second embodiment of the present invention shown selectively interconnected to a brake pedal, the broken lines showing environment only for illustrative purposes only and forming no part of the claimed design;

FIG. 11 is a front elevation view of the invention illustrated in FIG. 9;

FIG. 12 is a rear elevation view of the invention illustrated in FIG. 9;

FIG. 13 is a right side elevation view of the invention illustrated in FIG. 9; and,

FIG. 14 is a left side elevation view of the invention illustrated in FIG. 9.
